REINHARD HILDEBRAND, OF WEBSTER GROVES, MISSOURI, ASSIGNOR TO FULTON IRON WORKS COMPANY, OF ST. LOUIS, MISSOURI, A CORPORATION OF DELAWARE.

FUEL-FEEDING DEVICE FOR INTERNAL-COMBUSTION ENGINES.

Application filed August 16, 1924. Serial No. 732,490.

This invention relates to fuel-feeding devices for internal combustion engines, and more particularly to a fuel-feeding device adapted for use in an engine of the Diesel type wherein liquid fuel is atomized in the combustion chamber. To obtain the maximum efficiency, the entire charge of liquid fuel should be injected in a finely divided condition to form a mist in the highly heated compressed air in the combustion chamber. Heretofore measured charges of liquid fuel have been forced under a very high pressure through a fuel-atomizing nozzle adapted to form the desired mist when the liquid fuel is moving at the required velocity through the atomizing elements, but it is obvious that a non-uniform velocity will result in a non-uniform atomization of the fuel. Consequently, to obtain the highest efficiency, the fuel should be transmitted through the atomizing nozzle at a substantially uniform velocity.

Prior to this invention, quick-acting pumps have been used to force the charges of liquid fuel through the atomizers in the combustion chambers. The pump plungers perform their functions during very brief periods of time, and in fact the fuel-feeding operation is so brief that it results in an irregular condition, which I believe was not recognized prior to the present invention. In the ordinary fuel-feeding system, the condition to which I will refer causes the liquid fuel to pass through the atomizing nozzle at a non-uniform velocity, and owing to the variation in the speed and pressure, some of the liquid fuel issues from the nozzle in the form of relatively large drops which are not entirely consumed in the combustion chamber.

Even if it is assumed that the plunger of the ordinary fuel-feeding pump moves at a uniform speed during the entire fuel-feeding operation, there will be an appreciable undesirable variation in the velocity of the fuel at the injector. To understand this point, the speed and pressure of the incoming charge should be considered, and it will be apparent that the pressure should be instantly relieved at the end of each fuel-feeding operation, for a very gradual reduction in the pressure would result in a gradual reduction in the velocity at the nozzle. This is especially true in a system wherein the volume of the charge is determined by

a valve which controls the discharge of excess fuel from the inlet passage leading from the pump to the fuel injector, the pump piston being permitted to discharge excess fuel which escapes through said valve instead of passing to the injector. However, in a system of this kind, the pump usually forces the fuel to the injector under a pressure of several thousand pounds per square inch, and it is obvious that a very gradual reduction of this pressure would result in a non-uniform spray at the injector and imperfect combustion of the fuel. When the measuring valve is opened to discharge the excess fuel passing from the pump, the pressure should be instantaneously reduced to immediately discontinue the delivery of fuel through the restricted passages of the fuel injector.

In the ordinary systems of this type, the excess fuel passing from the pump is conducted from the measuring valve through a long restricted return duct leading back to the fuel reservoir, and even though the valve is quickly opened, the fuel under a pressure of several thousand pounds cannot freely escape through said return duct, so the fuel is permitted to escape from the nozzle in the form of relatively large drops at the end of each fuel-feeding operation.

One of my objects is to quickly relieve the fuel pressure at the end of each fuel-feeding operation, and to thereby avoid or minimize the imperfect combustion which has heretofore resulted from a more gradual reduction of the pressure. Briefly stated, the fuel-feeding system may include a pump delivering excess fuel to an inlet passage leading to the injector, and a measuring valve controlling the discharge of excess fuel, the latter being returned through a duct leading to the fuel reservoir. In the preferred form of the invention, a relatively large air chamber is located adjacent to the measuring valve, and this chamber is in free communication with the intake end of the return duct. When the valve is opened, the excess fuel rapidly enters said duct, and some of this fuel freely escapes into the air chamber, so the free outlet thus established will immediately reduce the pressure to such an extent that substantially all of the excess fuel will escape through said outlet.

With the foregoing and other objects in

view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the 10 claims hereunto appended.

Fig. I is a section, with some parts in elevation, showing a fuel-feeding device embodying the features of this invention.

Fig. II is a vertical section on the line 15 II—II in Fig. I.

1 designates a portion of an internal combustion engine provided with a combustion chamber 2 and a fuel-atomizing nozzle 3 for the discharge of fuel into said chamber. 20 The fuel-feeding device preferably comprises a cylindrical pump chamber 4 and a cylindrical plunger 5 conforming to the shape and diameter of the pump chamber. The fuel atomizing nozzle 3 is provided with 25 an inlet passageway leading from the end wall of pump chamber 4 to the nozzle 3, said passageway being formed partly by a pipe 6 which connects a block 7 to the nozzle, and partly by a passage 8 leading from the 30 end of the pump chamber to said pipe.

The pump plunger 5 is in the form of a tube provided with a longitudinal passage 9 for the admission of liquid fuel to the pump chamber 4 and having an inlet valve 10 at 35 its upper end to prevent return flow of the liquid. 11 designates a spring tending to retain the inlet valve on its seat. A discharge valve 12 is located in the discharge passage 8 to prevent return of the liquid to the pump 40 chamber.

A fuel reservoir 13 is provided with a discharge pipe 14 leading to an annular recess 15 formed around the tubular plunger 5, the latter having ports 16 communicating 45 with said-recess to admit the liquid fuel to the inlet passage 9 in the plunger.

To illustrate a suitable means for reciprocating the pump plunger, I have shown an eccentric 17 on a rotary shaft 18, a connecting rod 19 with a forked lower end mounted on said eccentric and having a curved upper end 20 seated in a socket 21 formed in a crosshead 22, the latter having a striking finger 23 adapted to engage an 55 abutment member 24 extending from the lower end of the plunger 5. A spring 25 is interposed between the abutment member 24 and a shoulder 26 to serve as means for restoring the plunger. A spring 27 is interposed between a collar 28 on the crosshead 22 and a shoulder 29 to restore the crosshead, said shoulder 29 being formed in a threaded tube 30 which serves as a stop to limit the downward motion of the plunger. The 60 threaded tube 30 is adjustable vertically to 65

vary the stroke of the plunger, thereby varying the quantity of liquid to be discharged from the pump.

A tubular valve guide 31 is provided with a valve 32 adapted to establish communication between the inlet passage 8 and a return duct 33 leading to a pipe 34 which extends into the fuel reservoir 13. A spring 35 tends to retain the valve 32 on its seat. An operating rod 36 is slidably mounted in 75 a guide 37 and provided with an adjustable screw 38 adapted to strike the lower end of valve 32. The means for lifting the rod 36 comprises a lever 39 pivoted on a rod 40 and adapted to be engaged by the collar 28 on the 80 crosshead 22. A thrust member 41 transmits motion from the lever 39 to the rod 36. 42 designates a restoring spring interposed between the guide 37 and a flange on the lower end of rod 36. 85

To discharge the liquid through the nozzle at a uniform velocity, the pump plunger should move at a uniform speed during the fuel-feeding operation, but the eccentric 17 moves the striking finger 23 at a non-uniform speed. During the beginning and end of each stroke the striking finger 23 moves at a non-uniform and relatively low speed, but during the middle period of the stroke the speed is much greater and substantially 90 uniform, so this middle period of the upward stroke is preferably utilized to force the liquid fuel through the atomizing nozzle. 95

At the beginning of the upward stroke, the striking finger 23 moves toward the central 100 abutment on the member 24 at the bottom of the plunger 5, and during the middle portion of the stroke the said finger engages said abutment to actuate the plunger and force the fuel from the nozzle 3. Thereafter, while the pump plunger continues to move upwardly at a gradually decreasing speed, the valve 32 is open to permit return of fuel from the inlet passage 8, through duct 33 to the reservoir 13. Therefore the 110 pump plunger 5 is moving at a substantially uniform speed while the fuel is passing through the nozzle 3, and one of my objects is to obtain a uniform velocity through the nozzle during the entire period in which 115 the fuel is entering the combustion chamber.

During each upward stroke of the pump plunger, the inlet valve 10 is closed and liquid is drawn from the reservoir 13 to the interior of the plunger, while the discharge 120 valve 12 is open to permit free escape of liquid from the pump chamber 4. During each downward stroke of the plunger, the discharge valve 12 is closed while the inlet valve 10 is open to admit fuel to the pump 12 chamber 4.

The valve 32 is a regulating element adapted to control the delivery of fuel to the injector 3, and the means for operating this valve can be adjusted in any suitable 13

manner to measure the fuel. As an illustration of one form of adjustable operating means, I have shown the screw 38 which strikes the lower end of the valve to open the same.

The fuel is usually pumped to the injector 3 under a pressure of several thousand pounds per square inch, so as to effectively atomize the liquid in the combustion chamber, and this pressure should be maintained throughout the fuel-injecting operation. When the valve 32 is opened to discharge the excess fuel passing from the pump, the pressure should be immediately decreased to such an extent that no substantial amount of fuel will pass from the nozzle 3 under the decreased pressure.

Attention is therefore directed to the large air chambers 50 formed at opposite sides of the valve 32 and located adjacent thereto, said chambers being conveniently formed by drilling the block 7 and by using plugs 51 to close the lower ends of the drilled holes. The upper end of the valve guide 31 has a central port or passage providing an outlet port for the excess fuel discharged from the pump, and said guide is also provided with a peripheral channel 52 and radial ports leading from said central port to said channel 52. This channel is in direct communication with the return duct 33 and also with short ports 53 leading into the large air chambers 50. Consequently, when the measuring valve 32 is opened, the excess fuel under an extremely high pressure is suddenly released and divided into three streams, two of which pass freely through ports 53 and into the air chambers, while the other flows through the return duct 33. The pressure is thereby quickly relieved to prevent continued discharge through the fuel atomizing nozzle 3. It is to be understood that the nozzle may be of any suitable design with restricted passages requiring a substantial pressure to force liquid fuel therethrough.

The liquid fuel entering the air chambers 50 compresses the air above the liquid, and at a later period the compressed air forces the liquid through the ports 52 and into the return duct 33.

I claim:

1. An internal combustion engine provided with a fuel injector having an inlet passageway for the admission of liquid fuel

through the injector, a pump whereby the liquid fuel is forced through said inlet passageway, said passageway having an outlet for the discharge of excess fuel, said outlet being formed between said pump and injector, a valve controlling the discharge through said outlet, a return duct leading from said outlet, a pressure-reducing air chamber adjacent to said valve, and a duct leading from said return duct to said air chamber, said air chamber being in free communication with said outlet to quickly reduce the pressure of the excess fuel escaping therethrough.

2. An internal combustion engine provided with a fuel injector having an inlet passage for the admission of liquid fuel through the injector, a pump whereby the liquid fuel is forced through said inlet passageway, a reservoir through which liquid fuel is supplied to said pump, said inlet passageway having an outlet port between said pump and injector so as to provide for the discharge of excess fuel, a return duct leading from said outlet port to said reservoir, a valve controlling the discharge through said outlet port, a pressure-reducing air chamber, and a duct communicating with the intake end of said return duct and with said pressure-reducing air chamber whereby the pressure of the excess fuel escaping at said valve is quickly reduced.

3. An internal combustion engine provided with a fuel injector having an inlet passage for the admission of liquid fuel through the injector, a pump whereby the liquid fuel is forced through said inlet passageway, a reservoir through which liquid fuel is supplied to said pump, said inlet passageway having an outlet port between said pump and injector so as to provide for the discharge of excess fuel, a return duct leading from said outlet port to said reservoir, an automatic valve controlling the discharge through said outlet port, pressure-reducing air chambers located adjacent to said valve, and ducts leading from said return duct to said pressure-reducing air chambers, said air chambers being in free communication with said return duct and outlet port so as to quickly reduce the pressure of the excess fuel therein.

In testimony that I claim the foregoing I hereunto affix my signature.

REINHARD HILDEBRAND.
